US00D860983S

(12) **United States Design Patent** (10) **Patent No.:** **US D860,983 S**
(45) **Date of Patent:** ** *Sep. 24, 2019

(54) **CASE FOR ELECTRONIC
COMMUNICATIONS DEVICE**

(71) Applicant: **SPIGEN KOREA CO., LTD.**, Seoul (KR)

(72) Inventor: **Ji Hyun Kim**, Seoul (KR)

(73) Assignee: **SPIGEN KOREA CO., LTD.**, Seoul (KR)

(*) Notice: This patent is subject to a terminal disclaimer.

(**) Term: **15 Years**

(21) Appl. No.: **29/629,027**

(22) Filed: **Dec. 11, 2017**

(51) LOC (12) Cl. **14-03**
(52) U.S. Cl. **USPC D14/250**

(58) **Field of Classification Search**

(57) **CLAIM**

The ornamental design for a case for electronic communications device, as shown and described.

DESCRIPTION

FIG. 1 is a front perspective view of a partially transparent case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines, and unshaded surfaces bounded by broken lines, depict parts of the article's appearance that form no part of the claimed design.

1 Claim, 8 Drawing Sheets
